A. H. WOOD.
GAS BLOWPIPE.

No. 40,376.

Patented Oct. 20, 1863.

UNITED STATES PATENT OFFICE.

ALONZO H. WOOD, OF BOSTON MASSACHUSETTS.

IMPROVEMENT IN GAS BLOW-PIPES.

Specification forming part of Letters Patent No. 40,376, dated October 20, 1863.

To all whom it may concern:

Be it known that I, ALONZO H. WOOD, of Boston, in the county of Suffolk and State of Massachusetts, have invented an Improved Gas Blow-Pipe, of which the following is a full, clear, and exact description, reference being had to the accompanying drawings, making part of this specification, in which—

Figure 1 is a perspective view of my improved apparatus. Fig. 2 is a vertical section through the same; Fig. 3, details to be referred to hereinafter.

My invention relates to that class of blow-pipes in which ordinary illuminating-gas is burned, and which are used by jewelers and other workmen on the bench for soldering and other purposes where an intense heat is required; and it consists, first, in the employment of one or more reservoirs for containing water or other volatile substances, provided with a means for heating the same so as to generate vapor, which is commingled with the gas and flame, and adds to the intensity of the heat; secondly, in a peculiar device, which, by nearly excluding the air from the gas before it is burned, causes the flame (which, when used for heat, is nearly colorless) to be changed so as to emit a bright light, which can be used for illuminating purposes by the workman when required.

To enable others skilled in the art to understand and use my invention, I will proceed to describe the manner in which I have carried it out.

In the accompanying drawings, A is the base, which is made hollow, so as to form a reservoir for water or other volatile substance, which is poured in at an opening provided with a screw plug, a. A passage, b, for the gas is formed in the base A, which terminates in a tip or delivery, c. At the other end this passage is tapped, and has screwed into it a short pipe, B, to which the gas is conducted by a flexible pipe or other suitable means, and the pipe B is furnished with a regulator, C, so as to regulate the supply of gas.

D is a cap, which is screwed into the top of the base A, and is furnished with prongs or arms d, which extend down into the water, as seen in Fig. 2, for a purpose that will be hereinafter described. This cap D is provided with holes e, for the purpose of admitting air,

which is commingled with the gas before it is burned, and thus greatly intensifies the heat of the flame. A screw-thread is turned within the center of this cap-piece D of a size sufficient to admit the screw-thread on the lower end of the upright tube or pipe E, of brass or other suitable metal. Another circular cap, F, fits on the lower end of this tube, and can move up and down thereon, so as to expose or cover the holes e of the lower cap-piece, D. The cap F has its edge milled for ease of raising and lowering the same. When the cap F is screwed down to cover the holes e of the cap D, air is only admitted through the holes f in the cap F, and passes into the annular cavity on its under side and through the holes e, a small supply of air being necessary for the proper combustion of the gas and to prevent it from smoking when used in so large a jet or delivery.

For the purpose of still further reducing the supply of air, a circular plate, g, is fitted over the cap F, and is furnished with holes h. This plate g may be turned so as to bring the holes h immediately over the holes f, or so as to close or partially close them, and may be then secured in place by the screw-nut i, which works on a screw-thread on the upper part of the cap F.

k are wires passing through flanges l and m, surrounding the tube E, and serve to transmit the heat to the tube E and prongs d, Fig. 2, for the purpose of heating the water so as to produce vapor, which is commingled with the gas to add to the intensity of the heat. I have found that without these wires k the lower portion of the tube E will remain cool. When a less degree of heat is required, the size of the orifice at the top of the tube E may be contracted by inserting a tube, n, having an opening of the size desired, as seen in Fig. 3.

H is another receptacle for holding water or other volatile substance, surrounding the tube E and wires k, and is suspended on the flange m by a turned edge at its top. The water within this reservoir H receives heat through the casing o, from the radiation of the heat of the wires k, and through the flange m.

It is obvious that the reservoirs may be used separately or together, as may be desired.

It will be seen that the vapor from the res-

ervoir H is mixed with the flame outside of the tube E, while that from the reservoir A is mixed with the gas inside the tube E.

Operation: The reservoirs being filled with water or other volatile substance, a supply of gas is admitted into the passage b and through the tip e into the tube E, the cap F being screwed up so as to admit air through the holes e, which passes between the prongs d, and is then mixed with the gas as it rises in the tube E, at the top of which it is burned, producing a flame which is nearly colorless and possesses an intense degree of heat. The wires h extend into the flame, and thus transmit heat to the tube E and prongs d and to the casing o and flange m, which heats the water in the reservoirs, generating vapor, which, as it rises, is commingled with the gas and flame for the purpose of still further intensifying the heat. The flame may be instantly changed, so as to emit a bright light when required, by screwing down the cap F so as to cover over the holes e, a small supply of air, sufficient to prevent it from smoking, being

admitted through the holes f, as before described.

I have spoken of the rods or wires h for the purpose of transmitting heat to the prongs d; but it is obvious that other means may be employed to effect this object without departing from the spirit of my invention.

What I claim as my invention, and desire to secure by Letters Patent, is—

1. The employment, in a gas blow-pipe, of one or more reservoirs for containing water or other volatile substance, and provided with a means of heating the same, so as to produce vapor to commingle with the gas and flame for the purpose of intensifying the heat, substantially as described.

2. The cap F, provided with holes f, and so arranged as to control the admission of air through the holes e, in the manner and for the purpose substantially as herein described.

A. H. WOOD.
